CLAIM

The ornamental design for combined back support and neck support pillow of synthetic foam, as shown and described.

DESCRIPTION

FIG. 1 is a top, front and right side perspective view of a combined back and neck support pillow of synthetic foam, showing our new design;

FIG. 2 is a left side elevational view thereof;

FIG. 3 is a rear elevational view thereof; and,

FIG. 4 is a bottom plan view thereof.

The convoluted foam pattern, fragmentarily shown in FIG. 1, is understood to extend throughout the area represented.
